GAME BOARD

Marvin S. Hecker, 10 E. 85th St., Manhattan, N.Y.

Filed Aug. 21, 1961, Ser. No. 66,439

Term of patent 14 years

(Cl. D34—5)

I claim:

The ornamental design for a game board, substantially as shown.
